UNITED STATES PATENT OFFICE

LEONARD J. DAVIES, OF RUGBY, ENGLAND, ASSIGNOR TO GENERAL ELECTRIC COMPANY, A CORPORATION OF NEW YORK

THERMIONIC VALVE

Application filed December 12, 1928, Serial No. 325,632, and in Great Britain December 13, 1927.

This invention relates to thermionic valves in which the self-capacity between the anode and control electrode is substantially eliminated by means of an additional screen electrode in the form of a grid which is disposed between the control grid and the anode, which screen electrode is maintained at a fixed potential, usually of a value somewhat lower than that of the anode.

10 The object of this invention is to provide a construction for such valves which will enable better operating constants to be obtained, and which will simplify the manufacture thereof.

15 The invention consists in forming the anode as a flat plate which is surrounded on both sides by the screen electrode shaped as a flattened cylinder.

In carrying the invention into effect, the 20 anode may consist of a single plate arranged on one side of a filamentary cathode in the form of a V, or of two parallel plates arranged on either side of the cathode. In both cases the screen electrode preferably consists 25 of a wire wound helically about two supporting wires lying in the plane of the anode, or of each section thereof, so that the screen is closely spaced therefrom. The control electrode may also consist of a wire grid in the 30 form of a flattened cylinder surrounding the cathode. Where a single plate is employed as anode, the control electrode may be a flat or curved wire grid arranged between the cathode and the screen electrode, but the flattened cylindrical construction is also prefer- 35 ably employed in this case since the manufacture of this form of grid is perhaps more simple. The several electrodes may be supported by wires which are sealed into the 40 usual press or pinch, and certain of these wires may be employed to conduct the necessary current or potential to the electrodes. The leading-in wire for the control electrode, however, is preferably led out of the enclosing 45 envelope through the end remote from the pinch, as by this means the capacity between the control electrode and the anode is still further reduced.

If it be desired to construct a valve in which 50 a third grid is used either immediately next

to the filament or between the screen-grid and the anode in order to improve the operating constants of the valve or to ensure stability in operation, then the method of construction described is still preferred, and the 55 third grid may be interposed either as a plane member situated between the control-grid and the screen-grid or as a wire grid in the form of a flattened cylinder coaxial with the screen grid.

An electrode construction in accordance with the invention is illustrated in the accompanying drawings in which Fig. 1 is a perspective view, while Fig. 2 is a diagrammatic view of a modified construction.

In the construction illustrated a single plate anode 1 is supported by a leading-in wire 2 sealed into a pinch 3 and extends in a direction parallel to the main axis of the enclosing envelope 4 of the device. Surrounding the anode is a screen consisting of a helical wire grid 5 in the form of a flattened cylinder. This grid is supported by two wires 6 and 7 extending parallel to the edges of the anode and attached to a metallic plate 8, which closes the end of the screen electrode nearest the pinch and has an aperture through which the anode lead passes, and is supported by a lead wire (not shown) sealed into the pinch. This plate may, if desired, have depending flaps 9 which assist in protecting the pinch from electron bombardment, and increase the shielding effect of the screen electrode. The other end of the screen electrode is also closed by a plate 10 attached to the screen support wires, which also have short wires 11 welded to them, which wires are embedded in a glass rod or bead 12. This bead also carries a hook 13 for supporting the bight of a V-shaped filamentary cathode 14, which is disposed parallel to the anode and has its ends attached to leads also sealed into the pinch. Embedded also in the bead are short wires 15 which support a wire grid 16 of flattened cylindrical shape which surrounds the cathode, and forms the control grid. As will be observed from the drawings, the control member is positioned remote from the plane of the anode. A lead 17 to this grid is sealed 100

into the end of the envelope remote from the pinch, so as to reduce the anode-grid capacity still further. Nickel or molybdenum may be used for the various support wires employed, while nickel is preferably used for the anode and the other metallic plates employed in this construction.

In the modified construction shown in Fig. 2 the electrodes are in part supported by a rectangular framework consisting of a metal plate 21, preferably of nickel or molybdenum, and two metallic wires 22 attached to one end to the plate, and having their other ends embedded in an insulating member 23, preferably a glass rod, arranged parallel to the plate, which is itself supported by wires sealed into a glass press or pinch. A filamentary cathode 24 of V-shape has its bight supported by a metallic hook 25 sealed into the glass rod and its two ends supported by leading-in wires 26 which project through holes in the metal plate, and which are sealed into the pinch. The control grid which immediately surrounds the cathode is in the form of a flattened cylinder 27 supported by stiff wires 28 lying in the plane of the filament, which are sealed into or otherwise supported by the glass rod. The anode consists of two parallel rectangular plates 29 of nickel or the like which are supported by wires 30, only one of which is shown, sealed into the pinch and electrically connected to one another. These plates are arranged on opposite sides of the cathode, to which they are parallel. Surrounding each anode plate is a grid 31 of flattened cylindrical shape which is closely spaced therefrom. These grids are electrically connected and constitute the screen electrode. They are each supported by wires 32 lying in the plane of each anode plate and close to the edges thereof, these wires being attached to the frame plate, which thus constitutes an integral part of the screen electrode and greatly assists in screening the anode from the control grid. One of the support wires for the frame plate is taken through the pinch, and permits of an operating potential being supplied to the screen electrode. The leads to the anode and cathode are also taken through the pinch, but that for the control electrode is taken through the other end of the enclosing envelope, for the reason stated above.

The construction described may be more readily manufactured than previous constructions of valves with screen electrodes, and the characteristic curve of the valve may be made to conform more closely to a desired outline.

What I claim as new and desire to secure by Letters Patent of the United States is:

1. An electron discharge device comprising an electron emitting cathode, an anode consisting of a plurality of flat members, screen grids in the form of flattened cylinders

surrounding said members, and a control grid in said device for cooperating with said cathode and anode.

2. An electron discharge device comprising an electron emitting cathode, and an anode 70 consisting of a plurality of members, screen grids surrounding said members and a control grid in said device for cooperating with said cathode and anode, said control grid and cathode being positioned between said 75 anode members.

3. An electron discharge device comprising an electron emitting cathode, an anode consisting of a plurality of flat members, screen grids in the form of flattened cylinders 80 surrounding said members, and a control grid in said device for cooperating with said cathode and anode, said control grid surrounding the cathode and being positioned intermediate said anode members.

In witness whereof, I have hereunto set my hand this 20th day of November, 1928.

LEONARD J. DAVIES.
